D. A. WEDMORE.
METALLIC REINFORCE FOR CONCRETE CONSTRUCTION.
APPLICATION FILED FEB. 21, 1908.

919,100.

Patented Apr. 20, 1909.

UNITED STATES PATENT OFFICE.

DANIEL A. WEDMORE, OF PHILADELPHIA, PENNSYLVANIA, ASSIGNOR TO PHILADELPHIA STEEL & WIRE CO., OF PHILADELPHIA, PENNSYLVANIA, A CORPORATION OF NEW JERSEY.

METALLIC REINFORCE FOR CONCRETE CONSTRUCTION

No. 919,100.

Specification of Letters Patent. Patented April 20, 1909.

Application filed February 21, 1908. Serial No. 417,108.

To all whom it may concern:

Be it known that I, DANIEL A. WEDMORE, a citizen of the United States, residing in Philadelphia, Pennsylvania, have invented certain Improvements in Metallic Reinforces for Concrete Construction, of which the following is a specification.

My invention relates to reinforced concrete construction; and the object of my invention is to provide unitary reinforcing means for a beam, girder, column or other portion of the same that may be constructed in the shop, shipped to the job in a folded condition and then set up in the position of use in precisely the same condition as originally set up in the shop, thus materially facilitating the erection work.

My invention is fully shown in the accompanying drawings, in which:

- 20 Figure 1, is a perspective view of reinforcing means for a beam or girder, showing the same in the finished form ready for the insertion of the longitudinal reinforcing bars after being placed upon the centering to receive the concrete; Fig. 2, is a side elevation of the reinforcing means, showing it in a collapsed or folded condition; Fig. 3, is a cross sectional view of the reinforcement in place in the concrete forming the beam; Fig. 4, is a 25 perspective view of reinforcing means for a post or column as erected in the shop and as ready for use on the job; Fig. 5, is an elevation of the same, showing the same in the collapsed or folded condition; Fig. 6, is a 30 perspective view of the beam reinforcement showing a modification in the method of connecting the elements of the same together; Fig. 7, is a view showing the structure of Fig. 6, collapsed; Figs. 8, 9, 10 and 11, are perspective views of locking members or ties for 35 securing the elements of the structure together, and Figs. 12, 13 and 14, are perspective views illustrating the manner of securing the elements of the reinforcing structure 40 by said tying devices.

The present practice of reinforcing concrete structures is, of course, too well known to require explanation or detailed description. The common method of procedure in 45 the reinforcing of beams, girders or columns, is to either build the entire reinforcing element on the job or to have the structure rigidly built up in its final form and shipped to the place of use, there to receive the heavier

reinforcing bars, or, in some instances, carrying the same with them.

In the use of reinforcing structures of this character, there are a number of difficulties, among which may be mentioned the excessive freight incident to the shipping of heavy structures, the bulk of the rigidly built structure, and in the case of the reinforcements erected on the job, the time that must be consumed in fitting and securing the elements of the same together. All of these objections are obviated by the use of the folding structure forming the subject of my invention.

In Fig. 1, 1 represents a series of stirrups of substantially the same size, shape and weight of metal which are distributed in any desired manner throughout the beam, in order to present the greatest support when in use. Combined with these stirrups is a series of light rods 2, in the present instance four in number, set at points which will represent substantially the four corners of the finished beam or girder. These bars are tied to the stirrups by means of wire ties 3, such as are illustrated in Figs. 8, 9, 10 and 11, and are of such a nature and so applied that when the structure is finished it may be collapsed longitudinally; the several ties for the longitudinal rods and stirrups forming hinges and permitting such action. Such collapsing or bending on the hinges will not affect the frictional engagement of the several parts, and hence there is no danger of any of the stirrups changing their position or working loose with respect to the longitudinal rods when such reinforcement is transported or when it is in use on the job. The arrangement of the ties shown in connection with Figs. 1 and 2, is such that the structure will fold vertically, the upper portion of the stirrup dropping down against the lower rods. In Figs. 6 and 7, however, the ties are arranged to permit horizontal folding of the structure. The same idea may be carried out in the erection of posts, columns or similar structures where the longitudinal reinforcing bars are vertically disposed, such, for instance, as is shown in Fig. 4, which illustrates rectangular spacing members 4 to which vertical rods 5 are tied by the members 3; the tying members being of the form illustrated in Figs. 8 and 11.

Referring to the enlarged views, Fig. 12, shows the connection between the longitudi-

nal bars or rods 2 and the upper portions of the stirrups 1; such tie being shown in the normal shape before use in Fig. 8. It consists of a wire member having two substantially parallel runs 10 and 10^a; the run 10 being longer than 10^a. The runs 10 and 10^a are joined by a loop 11 and said runs have hook portions 12 and 12^a, respectively. The loop of this tie is caught under one of the bars or rods; the runs 10 and 10^a are then brought down over the bar or stirrup projection lying at right angles to said bar or rod, and then the hooks 12 and 12^a in the order named are caught underneath the bar or rod in the manner clearly shown in Fig. 12. This arrangement permits either member to move with respect to the other, and when the members are assembled in proper relation to each other, such for instance as in the manner illustrated in Figs. 1 and 4, the structure may be readily collapsed as is illustrated in Figs. 2 and 5. It will be noted, however, that in order to permit this collapsing, the longitudinal rods are disposed below the lower cross-runs of the stirrups, the tie members forming with the bar or rod a bearing in which the projection of the stirrup may turn.

For use in connecting the lower cross-runs of the stirrup with the longitudinal bars or rods, I may use a tie member of the type shown in normal shape in Fig. 9 and in the position of use in Fig. 13. This tie member comprises a structure having a loop portion 13 to engage the rod, from which a run 14 extends, terminating in a hook 15 to engage the cross run of the stirrup. Another run 14^a extends from said loop portion 13 and passes over said rod and downwardly in a long curve or loop forming a support or foot; the end of said run being provided with a hook 15^a which is caught over the rod. The foot or support which this form of tie provides, raises the stirrup above the centering, as illustrated in Fig. 3, and at the same time obviates the necessity of using stirrups with their upper ends in engagement with the centering in order to raise them to the proper height to insure the required layer of concrete beneath the beam or girder.

In Fig. 10, I have shown a form of tie with two supports or feet. This may be used when the weight of the reinforcing bars is exceptionally great. This permits the use of straight arm projections for the stirrups. If the diagonally disposed arms are used, such as shown in Fig. 6, ties of the form shown in Figs. 8 and 11, may be employed. In Fig. 11, I have shown another form of tie member in its normal shape and in Fig. 14, in the position of use. This tie comprises a piece of wire doubled upon itself, and like the first mentioned tie shown in Figs. 8 and 12, it has runs of unequal length.

A long run 16 is provided with a hook 17 lying in the plane of a loop 18 connecting the runs, while a short run 16^a is provided with a hook 17^a lying in a plane at right angles to the hook 17. In the manner of attaching it to reinforcing rods which cross each other, as shown in the drawings, the hook 17^a may engage the horizontal rods, while the hook 17 may engage the vertical rods. Such arrangement, of course, depends upon which of the rods the loop 18 of the member is applied, for while it will act equally well when disposed in a position substantially at right angles to the structure shown in Fig. 14, it will be on the opposite side of the crossing portions of the rods.

It is obvious, of course, that other forms of ties capable of performing the function desired in structures of this character may be employed with equal facility, and my invention is not limited to the use of any specific form of tie or those shown herein.

I claim:

1. A collapsible reinforcement for concrete structures comprising a series of longitudinal members held in a plurality of planes, by a series of substantially vertical members having a plurality of hinged connections with said longitudinal members and bodily movable therewith.

2. A skeleton reinforcement for concrete structures comprising a series of stirrups the side members of which are disposed substantially in vertical planes, and longitudinal rods disposed substantially in horizontal planes hinged at top and bottom of said stirrups to form a bodily movable collapsing structure.

3. A reinforcement for concrete structures comprising independent series of substantially longitudinal and vertical members disposed substantially at right angles to each other in a plurality of horizontal and vertical planes, and means tying such members together at their crossing points but permitting movement of the same relatively to each other whereby the whole structure is bodily collapsible.

4. A reinforcement for concrete structures, comprising a series of stirrups, the side members of which are disposed substantially in vertical planes, and a series of longitudinal rods disposed substantially at right angles to said stirrups at top and bottom of the same, and tying means serving to secure said stirrups and rods together at their crossing points but permitting movement of the same relatively to each other whereby the whole structure is bodily collapsible.

5. In combination with a series of longitudinal rods disposed substantially in two horizontal planes, a series of members disposed substantially at right angles to said

- rods, and tying means at the crossing portions connecting said members and rods together yet serving to permit movement of the same relatively to each other whereby 5 the whole structure is bodily collapsible.
6. In combination with a series of longitudinal rods disposed substantially in two horizontal planes, a series of stirrups disposed substantially at right angles to said 10 rods, and tying means at the crossing portions connecting said rods and stirrups together and forming a joint to permit movement of one set of said members relatively to the other whereby the whole structure is 15 collapsible bodily.
7. A skeleton reinforcement for concrete structures, comprising a series of longitudinal rods disposed substantially in two horizontal planes, a series of members disposed 20 substantially at right angles thereto, ties for securing said members together, such ties permitting movement of one set of the same with respect to the other whereby the whole structure is bodily collapsible, and a support 25 or foot formed integral with one set of said ties.
8. A reinforcement for concrete structures, comprising a series of longitudinal rods disposed substantially in two horizontal planes, 30 a series of stirrups disposed substantially at right angles thereto, ties for securing said rods and stirrups together at their crossing points, such ties permitting movement of one set of said members with respect to the 35 other whereby the whole structure is bodily collapsible, and a support or foot formed integral with the ties connecting the lower runs of the stirrups and the rods adjacent the same.
- 40 9. A collapsible reinforcement for concrete structures, comprising pairs of longitudinal rods disposed in two horizontal planes, stirrups serving to connect together and space
- said rods apart, and connections hinging the rods and stirrups together and permitting movement of the same with respect to each other. 45
10. A collapsible reinforcement for concrete structures, comprising a series of longitudinal members disposed in a plurality of horizontal planes, a series of substantially vertical members connected to and serving to space apart said longitudinal members, and tying means connecting said members together and constructed to permit movement of each set of members with respect to the other, said vertical members having lower cross runs which lie on top of the longitudinal members. 55
11. A collapsible reinforcement for concrete structures, comprising a series of longitudinal members held in a plurality of planes, by a series of members disposed at right angles with respect to the longitudinal members, said two series of members being 60 hinged together for mutual support and forming a bodily movable structure. 65
12. A skeleton reinforcement for concrete structures, comprising longitudinal members disposed in a plurality of planes, a series 70 of other members disposed in a plurality of planes at an angle to the longitudinal members and connected to and serving to space apart the latter, tying means for the crossing points of said sets of members whereby 75 they are connected together and movable with respect to each other, and longitudinal reinforcing bars combined with said collapsible structure.

In testimony whereof, I have signed my name to this specification, in the presence of two subscribing witnesses.
